UNITED STATES PATENT OFFICE.

EDWARD J. DOLAN, OF PHILADELPHIA, PENNSYLVANIA, ASSIGNOR, BY MESNE ASSIGNMENTS, TO THE ACETYLENE HOUSE LIGHTING COMPANY, OF WEST VIRGINIA.

ACETYLENE-GAS BURNER.

SPECIFICATION forming part of Letters Patent No. 597,057, dated January 11, 1898.

Application filed March 12, 1897. Serial No. 627,202. (No model.)

To all whom it may concern:

Be it known that I, EDWARD J. DOLAN, a citizen of the United States, residing at Philadelphia, in the county of Philadelphia and State of Pennsylvania, have invented certain new and useful Improvements in Acetylene-Gas Burners; and I do declare the following to be a full, clear, and exact description of the invention, such as will enable others skilled in the art to which it appertains to make and use the same, reference being had to the accompanying drawings, and to the letters of reference marked thereon, which form a part of this specification.

This invention relates to certain new and useful improvements in gas-burners; and it relates more particularly to that class of burners which are especially designed for use in burning acetylene gas under pressure.

It has been found that in order to produce a uniform and smokeless flame it is necessary that a certain amount of oxygen should be supplied to the gas before it reaches the point of combustion, and in order to produce a flat, uniform, and smokeless flame it has heretofore been proposed to use a duplex burner in which the points of the burners have been inclined toward each other, so that the gas expelled from the burners under pressure will unite to form a flat flame.

The object of the present invention is to provide a burner suitable for use in burning acetylene gas under pressure, the construction of the burner being such as to dispense with the necessity of employing duplex burners and to provide a burner in which a flat uniform smokeless blaze is produced and in which provision is had whereby oxygen is supplied to the gas at a point within the burner intermediate of the point at which the gas is forced through a small flat opening and a corresponding outer slot or opening, at which latter point the blaze is seated.

To these ends and to such others as the invention may pertain the same consists in the novel construction of burner and in the peculiar arrangement, combination, and adaptation of parts, all as more fully hereinafter described, shown in the accompanying draw-

ings, and then specifically defined in the appended claim.

The invention is clearly illustrated in the accompanying drawings, which, with the letters of reference marked thereon, form a part of this specification, like letters of reference indicating the same parts throughout the several views, and in which drawings—

Figure 1 is a central vertical section through a burner constructed in accordance with my invention, the section being taken at right angles to the slots through which the gas passes. Fig. 2 is a central vertical section taken through the slots. Fig. 3 is a top plan view of the burner. Fig. 4 is a central vertical section taken through a modified form of the burner, and Fig. 5 is a top plan view of the burner shown in Fig. 4.

Reference now being had to the details of the drawings by letter, A designates a burner, or, as it is commonly known, a "burner-tip." It is preferably made of lava or other material of a like nature and is preferably in a single piece, as shown, consisting, essentially, of a body portion at the upper end of which is provided an enlarged circular or dome-shaped portion A², which portion A² is provided with a vertical transverse slot a, which slot opens into a chamber B. C is a gas-passage which extends longitudinally through the body and neck portions of the device and at its upper end is provided with an oval or enlarged crown or tip C², which conforms in shape to the form of the enlarged outer portion A² of the burner and is provided with an exceedingly narrow slot c, which slot c is in direct alinement with the larger outer slot a. The portion A² of the burner is provided with a series of small openings b, through which air is admitted to the chamber B, as shown.

The operation of the burner will from the foregoing description be readily understood. It will be seen that the gas in passing through the narrow slot c will be formed into a flat column or sheet, and the said column or sheet being forced through the outer widened slot or aperture a the blaze will be seated at the point at which the gas escapes through the outer slot a. Air, which enters through the

small openings B, will supply the gas with oxygen within the chamber B, and the gas, having thus been supplied with oxygen before it reaches the point at which the blaze 5 is seated, will produce a smokeless flame, as will be readily understood.

Although I have in Figs. 1, 2, and 3 of the drawings illustrated a burner which is made in a single piece, and I prefer this construction, still it is at once evident that the construction is susceptible of certain modifications. In Figs. 4 and 5 of the drawings I have shown one of these modifications, the burner illustrated in said figures consisting of two 15 separate parts, the inner tube being in this instance inserted within a hollow opening provided for its reception in the body portion of the burner.

Having thus described my invention, what

I claim to be new, and desire to secure by Letters Patent, is—

In a gas-burner of the character described, an inner slot or gas-passage, in direct alignment with a slot or gas-passage of greater width at the extreme point of the burner, a 25 chamber within the burner intermediate of the slots and lateral air-passages communicating with the said chamber at or above the horizontal plane of the inner slot, substantially as described and for the purpose specified.

In testimony whereof I affix my signature in presence of two witnesses.

EDWARD J. DOLAN.
